SEWING MACHINE SAFETY DEVICE

Hermann Gunther, Elizabeth, N. J., assignor to
The Singer Manufacturing Company, Elizabeth, N. J., a corporation of New Jersey

Application July 3, 1936, Serial No. 88,737

11 Claims. (Cl. 112—110)

This invention relates to a sewing machine and more particularly to a safety device for a sewing machine which performs a predetermined number of stitch-forming cycles and is then automatically brought to rest by a stop-motion device.

One of the objects of this invention is to provide an improved safety device which will prevent the work-clamp from being raised until the predetermined number of stitch-forming cycles has been completed, the usual trimmer mechanism operated to sever the threads, and the machine has come to rest.

Another object of this invention is to provide a safety device which may be readily applied to machines already in use and which is characterized by its compactness, durability and simplicity, and its provisions facilitating its accurate assembly and incorporation in existing machines.

A still further object of this invention is to provide an improved safety device which will prevent the presser-bar lifting lever from being raised when the machine begins its cycle of operations or to prevent the machine from being started until the presser-bar lifting lever is in its normal position.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

Figure 1 is a rear side elevation of a sewing machine showing my improved safety device applied thereto.

Figure 2 is a sectional view of the controlling cam and disk, taken along the line 2—2 of Figure 1.

Figure 3 is a perspective view of the clamp-locking disk or ring.

As represented, the machine is constructed with a frame comprising the cylinder-bed or work-arm 1 from which rises the standard 2 carrying a bracket-arm 3 terminating in a hollow head 4. Journaled within and longitudinally of the arm 3 is the main-shaft 5 from which is derived, through usual operative connections, the reciprocating movements of the needle-bar 6 carrying the needle 7. In practice, the needle 7 cooperates with a suitable loop-taker, not shown, within the free end of the hollow cylinder-bed 1.

The work is adapted to be clamped between the upper and lower members of a work-holder

which, in the particular embodiment illustrated, is moved to and fro over the work-support to position the stitches in accordance with the desired pattern. The present work-holder is of the general type disclosed in the patent to Barron No. 1,205,317, of November 21, 1916, and comprises the sliding bar 8 carrying a work-supporting plate 9 at the end adjacent the stitch-forming mechanism. Mounted on the bar 8 is a bracket 10 having at its free end a head 11 which carries the usual presser-bar 12 terminating in a work-clamp or work-holder 12' which is spring urged towards the plate 9. Projecting forwardly from the presser-bar 12 through a slot in the face of the head 11 is a rod 13 the extremity of which lies above and in the path of vertical movement of the arm 14 of a bracket-piece fixed to the lower end of the usual work-holder lifting bar 15 carried by the head 4.

The work-holder is moved longitudinally of the work-arm 1 by means of the usual cam slot 50 in the inner face of the controller cam wheel 16 (see Fig. 2), which imparts rocking motion to a lever 17. The motion of the lever 17 is communicated in a well known manner to the vertical post 18 rising from the rear end of the bar 8. The work-holder is vibrated laterally of the work-arm 1 about the post 18 as a pivot by means of the usual connections with the cam slot 19 in the outer face of the controller cam 16. The connections include the bell-crank lever 20, pitman 21, rock-shaft 22 and arm 23. The means for imparting longitudinal and lateral movements to the work-holder is fully described in the patent to Horton No. 1,051,998, of February 4, 1913.

This machine is provided with the usual thread-cutter, not shown, for cutting the threads at the end of the cycle of operation of the stitch-forming mechanism. The thread-cutter is operated from the stop-motion device, indicated generally as 8. The stop-motion device comprises the pivoted stop-lever 40 which includes the usual belt shifting guide arm 41 rigid with it. The stop-lever 40 carries the spring pressed plunger rod 42 adapted to engage the stopping cam 43 fixed to the pulley 44 which is fixed to the main-shaft 5. The cycle of operation of the machine is started by actuation of the angle lever 45 which causes the lever 40 to move to the right as viewed in Figure 1. This movement causes the belt-shifting guide 41 to shift the belt from the idler pulley 46 to the fast pulley 44 thereby starting the cycle of operation. The stop-lever 40 is locked in running position (the position shown in dotted lines in Fig. 1) by means of the catch 55

latch 48 mounted upon the frame 49 by means of the fulcrum screw stud 51 and is adapted to be tripped for disengagement of the stop-lever by means of the tripping stud 52 carried upon the inner face of the controller cam 16. The thread-cutting and stop-motion mechanism are fully described in the said Horton patent and further description is deemed unnecessary.

It will be understood that a machine of the present type when tripped into action, automatically performs a definite series of operations under control of the cam 16 and is then brought to rest by the stop-motion device. Operators of these machines often anticipate the moment that the cycle of operation is complete and press on a treadle which, in practice, is connected by a chain to the usual presser-bar lifting lever which is pivoted to the arm 3 at 25. The operator sometimes presses on the treadle and raises the presser-bar and work-holder before the machine has come to rest and when this occurs the thread or needle may be broken, or the thread-cutter may not have had time to operate and sever the thread close to the underside of the work. To make it impossible for the operator to raise the presser-bar by pressing on the treadle before the machine has come to rest I have provided the machine with an attachment which may be readily fixed to existing machines. The attachment comprises a ring 27 detachably secured to the outer face of the controller cam 16 by the screws 28 and a hardened steel finger 31 which is adjustably secured to a substitute presser-bar lifting lever 24 by the set screw 32, the lever 24 having a treadle-chain lug 24'. The controller cam is rotated 180° for each operative cycle of the machine and the ring 27 is formed with two diametrically opposite notches 29 and 30 in its periphery with which the finger 31 alternately registers when the machine is in stop position. It will be obvious from the foregoing that the finger 31 normally rides upon the periphery of the ring 27 and the ring 27 is so timed with the operation of the machine that the finger overlies one of the notches 29 or 30 only when the machine is in stop position and, therefore, the lever 24 can only be operated to lift the presser-bar when the machine has come to rest.

The ring 27 is made of cast iron and to prevent excessive wear on the edges of the notches 29 and 30 and also to provide means for accurately timing the point in the cycle of operation of the machine at which the lever 24 may be operated, hardened steel wear plates 33 are adjustably secured in grooves 36 in the periphery of the ring by the screws 34 which extend through slots 35 formed in the plates 33. It will be apparent that the screws 34 may be loosened and the plates 33 shifted in the grooves 36 to obtain the exact timing required and to compensate for wear of the parts.

In order to prevent the lever 24 from being actuated during the initial stitch-forming cycles and before the finger 31 rides out of the notch 65 the free end of the lever 24 may be extended to a point at which it will overlie the belt-shifting guide arm 41 when this arm is in the position indicated in dotted line in Fig. 1. As previously described the angle lever 45 is actuated to move the stop-lever 40 and belt-shifting arm 41 to the right as viewed in Fig. 1, and it will be obvious that if the lever 24 is depressed so as to raise the presser-bar 12 the free end 47 of the lever will prevent the belt-shifting arm 41 and stop-lever 40 from being shifted to the dotted line

position to start the machine. On the other hand, if the lever 24 is in the position shown in Figure 1 then the stop-lever 40 and belt-shifting arm 41 may be moved to the dotted line position to start the machine and it will be noted that when the arm 41 is in the position shown in dotted lines the lever 24 is locked so that it cannot be actuated to raise the work-clamp. Just prior to the end of the cycle of operation the stop-lever 40 and arm 41 are automatically shifted back to the full line position and therefore, the arm 41 is moved out of the way of the end 47 of the arm 24. However, the finger 31 is riding on the disk 27 at this point in the cycle and consequently the lever 24 cannot be actuated until the finger 31 overlies one of the notches 29 or 30 in the ring 27, at which time the machine has come to rest.

It will be apparent that the above described construction may be modified so that operation of the lever 24 is prevented by other movable parts of the stop-motion mechanism in place of the belt-shifting arm 41. While my invention is shown applied to a machine having a special form of work-clamp it will be obvious that other types of work-clamps may be used and my improved safety device may be embodied in various types of sewing machines that perform a definite series of operations and then come to rest.

Having thus set forth the nature of the invention, what I claim herein is:—

1. In a sewing machine adapted to perform a definite series of operations in combination stitch-forming mechanism including a reciprocating needle, a shiftable work-holder, a cam for controlling the shifting movements of said work-holder, manual means for raising and lowering said work-holder and means carried by said cam for preventing said work-holder from being raised until the machine has completed its series of operations.

2. In a sewing machine adapted to perform a definite series of operations, in combination, stitch-forming mechanism including a reciprocating needle, a work-holder, means for causing said needle and work-holder to vibrate relative to each other, a cam for controlling the series of operations of the machine, means for raising said work-holder, and means under control of said cam for preventing the work-holder from being raised until the machine has completed its series of operations.

3. An attachment for a sewing machine having a work-holder, means for raising said work-holder, and a rotatable cam, comprising a ring attachable to said cam and mechanism interposed between said ring and said raising means for preventing said raising means being operated except at predetermined intervals.

4. An attachment for sewing machines having a rotatable element, a work-holder and means for raising said work-holder, comprising a member adapted to be detachably secured to said rotatable element and means under control of said member for preventing operation of said raising means during the operation of the machine.

5. In a sewing machine adapted to perform a definite series of operations in combination, stitch-forming mechanism including a reciprocating needle, a stop-motion device, a cam for controlling the cycle of operation of the machine, a work-holder, a lever for raising and lowering said work-holder, a member on said cam and means under the combined control of said stop-

motion device and said member for preventing the lever from being actuated except at predetermined times to raise the work-holder.

to said lever and normally riding over the outer periphery of said ring, the notch in said ring being positioned and arranged to be in alignment with said finger only when the machine is at rest.

6. In a sewing machine adapted to perform a definite series of operations, in combination, stitch-forming mechanism including a reciprocating needle, a stop-motion device, a cam for controlling said stop-motion device, a work-holder, means for raising said work-holder, means under control of said stop-motion device for preventing said work-holder from being raised at the beginning of the cycle of operation and a member carried by said cam for preventing said work-holder from being raised until the machine has completed its cycle of operation and come to rest.

9. In a sewing machine adapted to perform a definite series of operations and then come to rest, in combination, stitch-forming mechanism including a reciprocating needle, a work-holder, a lever for raising said work-holder, means shiftable into the path of movement of said lever at the beginning of a series of operations to prevent said work-holder from being raised, and a second means for preventing said lever from being raised until the machine has come to rest.

10. In a sewing machine adapted to perform a definite series of operations in combination, stitch-forming mechanism including a reciprocating needle, a work-clamp, a stop-motion device including a pivoted lever, and a clamp lifting lever having interengaging relation with said lever.

11. In a sewing machine adapted to perform a definite series of operations, in combination, stitch-forming mechanism including a reciprocating needle, a work-clamp, a stop-motion device including a pivoted member, and a clamp-lifting lever, said member and said lever being so constructed and arranged that each is movable into the path of movement of the other.

HERMANN GUNTHER. 30

- 5 6. In a sewing machine adapted to perform a definite series of operations, in combination, stitch-forming mechanism including a reciprocating needle, a stop-motion device, a cam for controlling said stop-motion device, a work-holder, means for raising said work-holder, means under control of said stop-motion device for preventing said work-holder from being raised at the beginning of the cycle of operation and a member carried by said cam for preventing said work-holder from being raised until the machine has completed its cycle of operation and come to rest.
7. An attachment for a sewing machine having a work-holder, a lever for raising said work-holder, and a controller cam, comprising a finger carried by said lever and a ring adapted to be secured to said cam, said ring having a plurality of notches in its periphery which are adapted to underlie the finger on said lever at predetermined times, whereby said lever may be actuated to raise said work-holder.
8. A safety device for sewing machines having a work-holder, a lever for raising said work-holder and a cam for controlling the operation of the machine, comprising a ring actuated by said cam and having one or more notches in its outer periphery, and a finger adjustably secured
